CLAIM

The ornamental design for a cylinder, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top perspective view of a cylinder showing a new design;

FIG. 2 is a bottom perspective view of the cylinder illustrated in FIG. 1;

FIG. 3 is a top view of the cylinder illustrated in FIG. 1;

FIG. 4 is a bottom view of the cylinder illustrated in FIG. 1;

FIG. 5 is a front view of the cylinder; and,

FIG. 6 is a rear view of the cylinder.

The broken line boundaries and de-emphasized areas shown in gray-tone within the broken lines depict portions of the cylinder that form no part of the claimed design.
